(57) **CLAIM**

The ornamental design for a display screen or portion thereof with animated graphical user interface, as shown and described.

DESCRIPTION

FIG. 1 is a front view of a display screen or portion thereof with animated graphical user interface, in which a first embodiment of my animated graphical user interface is shown;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of a display screen or portion thereof with animated graphical user interface, in which a second embodiment of my animated graphical user interface is shown;

FIG. 9 is a front view of a second image thereof;

FIG. 10 is a front view of a third image thereof;

FIG. 11 is a front view of a fourth image thereof;

FIG. 12 is a front view of a fifth image thereof;

FIG. 13 is a front view of a sixth image thereof; and,

FIG. 14 is a front view of a seventh image thereof.

The subject matter in this patent includes a process or period in which an image changes into another image. The process or period forms no part of the claimed design. The dot-dash lines in the figures represent the bounds of the claimed design and form no part thereof. The broken lines shown within the dot-dash lines represent portions of the display screen or portion thereof with animated graphical user interface and form no part of the claimed design. The outermost broken lines shown in FIGS. 1 and 8 represent the article of manufacture and form no part of the claimed design.
